(57) **CLAIM**

The ornamental design for an underwater cleaning robot, as shown and described.

DESCRIPTION

FIG. 1 is a perspective view of an underwater cleaning robot showing my new design;

FIG. 2 is a front view thereof;

FIG. 3 is a back view thereof;

FIG. 4 is an enlarged left view thereof;

FIG. 5 is an enlarged right view thereof;

FIG. 6 is a top view thereof;

FIG. 7 is a bottom view thereof;

FIG. 8 is an enlarged view of the encircled area 8 of FIG. 1;

FIG. 9 is an enlarged view of the encircled area 9 of FIG. 1;

FIG. 10 is an enlarged view of the encircled area 10 of FIG. 1;

FIG. 11 is an enlarged view of the encircled area 11 of FIG. 2;

FIG. 12 is an enlarged view of the encircled area 12 of FIG. 5; and,

FIG. 13 is an enlarged view of the encircled area 13 of FIG. 6.

The broken lines shown on the drawings depict portions of the underwater cleaning robot that form no part of the claimed design. The dash-dot lines illustrate the boundary of the enlarged views and form no part of the claimed design.
